(57) **CLAIM**

The ornamental design for a camp stove, as shown and described.

DESCRIPTION

FIG. 1 is a perspective view of a camp stove showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line portions of the camp stove in FIGS. 1-7 represent portions of the camp stove and form no part of the claimed design.

1 Claim, 7 Drawing Sheets
